(57) **CLAIM**

The ornamental design for a surgical portal driver, as shown and described.

DESCRIPTION

FIG. 1 is a front perspective view of a first embodiment of a surgical portal driver showing our design;

FIG. 2 is a rear perspective view thereof;

FIG. 3 is a front view thereof;

FIG. 4 is a first side view thereof;

FIG. 5 is a rear view thereof;

FIG. 6 is a side view thereof, opposite that shown in FIG. 4;

FIG. 7 is another side view thereof, 90 degrees offset from that shown in FIG. 6;

FIG. 8 is another side view thereof, opposite that shown in FIG. 7;

FIG. 9 is an exemplary environmental view illustrating the surgical portal driver engaged with a working portal (also known as a guide cannula) according to embodiments of the present invention;

FIG. 10 is a front perspective view of a second embodiment of a surgical portal driver showing our design;

FIG. 11 is a rear perspective view thereof;

FIG. 12 is a front view thereof;

FIG. 13 is a first side view thereof;

FIG. 14 is a rear view thereof;

FIG. 15 is a side view thereof, opposite that shown in FIG. 13;

FIG. 16 is another side view thereof, 90 degrees offset from that shown in FIG. 15;

FIG. 17 is another side view thereof, opposite that shown in FIG. 16;

FIG. 18 is an exemplary environmental view illustrating the surgical portal driver engaged with a working portal (also known as a guide cannula) according to embodiments of the present invention;

FIG. 19 is a front perspective view of a third embodiment of a surgical portal driver showing our design;

FIG. 20 is a rear perspective view thereof;

FIG. 21 is a front view thereof;

FIG. 22 is a first side view thereof;

FIG. 23 is a rear view thereof;

(Continued)

FIG. 24 is a side view thereof, opposite that shown in FIG. 22;

FIG. 25 is another side view thereof, 90 degrees offset from that shown in FIG. 24;

FIG. 26 is another side view thereof, opposite that shown in FIG. 25; and,

FIG. 27 is an exemplary environmental view illustrating the surgical portal driver engaged with a working portal (also known as a guide cannula) according to embodiments of the present invention.

In the drawings, the broken lines depict environmental subject matter only and form no part of the claimed design.
